(57) **CLAIM**

The ornamental design for an integral luggage and tie down set for a vehicle rack, as shown and described.

DESCRIPTION

FIG. 1 is a perspective view of an integral luggage and tie down set for a vehicle rack showing my new design.

FIG. 2 is a top view thereof.

FIG. 3 is a front view, the rear being a mirror image thereof.

FIG. 4 is a bottom view thereof; and,

FIG. 5 is a side view, the opposite side being a mirror image thereof.

The broken-line showing of environmental structure in FIGS. 1 through 5 is for illustrative purposes only and forms no part of the claimed design.
